UNITED STATES PATENT OFFICE.

LAWRENCE H. MORSE, OF CLEVELAND, OHIO, ASSIGNOR TO THE AMERICAN MULTIGRAPH CO., OF CLEVELAND, OHIO, A CORPORATION OF OHIO.

PRINTING FORM.

Application filed July 6, 1926. Serial No. 120,620.

This invention relates to printing devices. An object is to provide an inexpensive printing form which may be easily built up to any desired length from articulated parts. 5 Another object is to provide a printing form, the parts of which may be comparatively cheaply manufactured and which will accommodate type of different pica in various arrangements. 10 A further object is to provide an articulated printing form which may be mounted flatwise as for a flat bed printing press or in arcuate form as on a printing drum.

Further objects and advantages of the invention will become apparent from the following description relating to the accompanying drawings, wherein I have shown my preferred form. The essential novel characteristics will be summarized in the 20 claims.

In the drawings Fig. 1 is a cross-sectional view taken through a multigraph machine showing a drum with my improved form assembled thereon, and a coacting impression roller, the paper feeding mechanism etc. being omitted; Fig. 2 is a plan view showing a number of rails and type; Fig. 3 is a perspective view of one of the rails; Fig. 4 is a perspective view of one of the type; Fig. 5 is a cross-section through a number of rails and type showing the relative position of such members when used on an arcuate support; Fig. 6 is a similar cross section showing the relative position of the rails and type when supported on a flat surface; Fig. 7 is a plan view of a flat chase showing different sized type assembled thereon.

In carrying out my invention I employ similarly formed rails, the rails being arranged to interlock with complete lines of type whereby the form may be assembled by composing a line of type onto a given rail, then sliding another rail onto the thus composed line of type and so on until the complete form is made up.

Referring in detail to the drawings and indicating the parts by suitable characters, A indicates the base frame of a multigraph machine, this machine being illustrated 50 merely for an example of the type of printing mechanism for which my invention is

adapted. B indicates generally the printing drum and C the cooperating impression roller. The drum is mounted on the frame by means of a shaft D and has a semi-circular type supporting portion E upon which the type forming the subject of this invention may be mounted. Suitable inking mechanism for the type may comprise an inking ribbon F carried by rolls G, the ribbon being wrapped around the outside of the drum to overlie the type, this being the usual multigraph inking device.

The rails 1, preferably comprise elongated bars having a uniform X-shaped cross-section, as shown in Fig. 3, wherein 2 indicates the enlarged side portions and 3 the reduced central portion. The type are shown in Figs. 4 and 5 as having dove tailed slots in their opposite sides as shown at 6. In assembling the complete form, the type setter may start with a single rail and form a single line of the type over one of the enlargements or slideways 2. He then slips another rail along the assembled line in the row of unoccupied slots 6 and continues in this fashion until the form is set up. The form may be held on a drum or any arcuate surface as shown in Fig. 1, wherein 10 indicates a securing block or strip having a dove tailed slideway 11 in one side thereof, this block being secured to the drum, as shown, by means of a series of screws, one of which is indicated at 12. Simultaneously with sliding the endmost rail 1' into the slideway in the block 10, the rail at the other end of the form, namely 1" may be slid into the slideway 13 in a block 14, shown as carried on a pivoted frame 15. This frame may consist of an elongated sheet metal plate having hooks 16 which may be sprung over the shaft D. When the form is so assembled on the drum, it may be put under tension by tightening a series of set screws, one being shown at 17, against the drum portion E. This causes all of the type slugs to bear at their bases upon the smooth surface of the drum portion E.

Fig. 5 shows the relative positions of the type and rails when placed on a curved surface and it will be noted that the outer side surfaces 2a of the enlargements are drawn

away from the web portions of the type and the beveled side surfaces 2^b are in intimate contact with the side surfaces of the dove tailed slots on the type. This of course 5 holds all the type firmly in place.

When the form is used flatwise as in a flat bed chase, (for example N in Fig. 7), the rows of type and rails are compressed together as by the usual printers' wedges 10 shown at W. This causes the type and rails to assume the relative positions shown in Fig. 6, wherein it will be seen that the surfaces 2^c on the rails are in intimate contact with the webs of the type, so that when a 15 given form is used in this fashion, the type are firmly held in place in the entire chase.

By my invention I may complete the form by using lines of slugs that are either individual type or linotype slugs of the same 20 pica or I may have some of the lines formed of different width, and if desired I may set up display type between the adjacent ends of short lines of regular type. In such case 25 the display type occupy the same length of form as do the several small lines with their rails.

Fig. 7 also shows the manner in which display type of a considerable larger size than the general form type are set up, such display type being indicated at 20 (Figs. 7 and 30 5). The block of display type may have at its ends regular or smaller type, as shown, it being understood that the display type size is determined by some multiple based on the 35 mean distance between two or more of the smaller type. It is to be remembered that such larger type may extend entirely across the form as shown at 5^a in Fig. 7, in which case no particular unit of measure is necessary. 40

Having thus described my invention, I claim:—

1. A printing device comprising a plurality of printing members having type characters thereon, rails arranged to be slid into interlocking engagement with the printing members and held thereby, said engagement permitting the device to conform to supporting surfaces of different character. 45

2. In combination, printing members having characters thereon, a series of retaining members interposed between parallel rows of such first named printing members, one of said members having a dove-tail groove and 55 the other having an enlargement engaging therewith and capable of being turned slightly therein whereby the form may be warped to conform to various supporting surfaces.

3. In a printing device, character bearing 60 printing members arranged in parallel rows, securing members interposed between the rows, said printing members and securing members being mutually shaped to interlock

with each other and thus, independently of other devices, to constitute a flexible form. 65

4. In a printing device, a plurality of lines of type members, rails interposed between the lines and in interlocking engagement with said type members, said engagement being such that when the device is 70 placed either in tension or compression, substantially all of the type members are held against movement in the direction of the lines of type.

5. A printing device comprising type 75 slugs having dove tail slots in their opposite sides, rails arranged to loosely fit said slots, and adjustable means for securing said printing device on a printing bed whereby the slugs and rails may be freely assembled 80 and thereafter stressed to cause the slugs and rails to be held in place by friction.

6. In combination, a printing drum, a slideway carried thereby, a plurality of type slugs, a plurality of rails having wedge head 85 shaped side edges, one edge of one rail fitting said slideway and the other edge interlocking with a row of slugs, other similar rails and slugs similarly assembled to form a blanket and an adjustable slideway carried 90 by the drum for engaging the last rail.

7. A printing form adapted for use interchangeably with a printing drum or flat chase, said form comprising rails arranged in rows and having their opposite sides enlarged, and type slugs arranged in lines between adjacent rails, said type slugs having dove tailed slots therein fitting over the enlarged sides of the rails. 95

8. A printing device comprising in combination a plurality of parallel rails having enlarged side edges, type members arranged in rows between enlarged side edges and having dove tailed slots in their opposite sides fitting over such adjacent rails. 100

9. A printing form comprising separate rails arranged in parallel rows, type members in interlocking engagement with adjacent rails, a portion of one line of type in the form being of substantially greater width 110 than others, whereby to support larger characters, and a plurality of short rails with type of smaller dimensions and arranged in alignment carrying said larger type.

10. A printing form comprising parallel 115 rails of a general X-shaped cross-section, and lines of type having dove tailed slots at their sides adapted to fit loosely but retentively over adjacent sides of such adjacent rails, whereby the form may be made up of 120 any convenient length and may be used either flatwise or in arcuate form.

In testimony whereof, I hereunto affix my signature.

LAWRENCE H. MORSE.
